238,032

TIE RACK

Thomas W. Duncan, 800 Tulip Lane,
Connersville, Ind. 47331

Filed Jan. 6, 1975, Ser. No. 538,608

Term of patent 14 years

Int. Cl. D6—08

U.S. Cl. D6—251

FIG-1

FIG-3

FIG. 1 is a front perspective view of a tie rack showing my new design, the rear being a mirror image thereof;

FIG. 2 is a top plan view thereof; and
FIG. 3 is a bottom plan view thereof.

I claim:

The ornamental design for a tie rack, substantially as shown and described.
